United States Patent Office

Des. 219,897
Patented Feb. 9, 1971

219,897

SHEATH

Clayton A. Laughlin, Minneapolis, Minn., assignor to
Arthur Salm Inc., Chicago, Ill., a corporation of Illinois

Filed June 20, 1969, Ser. No. 17,792

Term of patent 14 years

Int. Cl. D3—99

U.S. Cl. D87—1

FIG. 1.

FIG. 2.

FIG. 3

FIG. 4

FIG. 5

FIG. 1 is a front elevational view of a sheath for accepting both scissors and a letter opener embodying my new design;

FIG. 2 is a rear elevational view thereof;

FIG. 3 is a side elevational view thereof, the side opposite being a mirror image thereof;

FIG. 4 is a bottom plan view;

FIG. 5 is a top plan view.

I claim:

The ornamental design for a sheath, substantially as shown and described.
